US0D1063102S

(12) **United States Design Patent** (10) **Patent No.:** **US D1,063,102 S**
(45) **Date of Patent:** **** Feb. 18, 2025**

(54) **ULTRAVIOLET SANITIZING FIXTURE**

(71) Applicant: **LUMENLABS LLC**, Poway, CA (US)

(72) Inventors: **Kevin C. Baxter**, Tulsa, OK (US); **Min Shi**, Shanghai (CN)

(73) Assignee: **Lumenlabs LLC**, NV (US)

(**) Term: **15 Years**

(21) Appl. No.: **29/802,920**

(22) Filed: **Aug. 9, 2021**

(57) **CLAIM**

The ornamental design for a ultraviolet sanitizing fixture as shown and described herein.

DESCRIPTION

FIG. 1 is a front elevation view of an ultraviolet sanitizing fixture, showing our new design;

FIG. 2 is a bottom plan view thereof;

FIG. 3 is a side elevation view thereof;

FIG. 4 is a top plan view thereof;

FIG. 5 is a side elevation view thereof; and,

FIG. 6 is a rear elevation view thereof.

In the drawings, the equal-length broken lines depict elements of the ultraviolet sanitizing fixture that form no part of the claimed design.
